CLAIM

The ornamental design for a foldable face mask, as shown and described.

DESCRIPTION

FIG. 1 is a front perspective view of a foldable face mask shown in a used condition, showing our new design;

FIG. 2 is another perspective view thereof;

FIG. 3 is a front elevation view thereof;

FIG. 4 is a rear side elevation view thereof;

FIG. 5 is a left side elevation view thereof;

FIG. 6 is a right side view thereof;

FIG. 7 is a top plan view thereof;

FIG. 8 is a bottom plan view thereof; and,

FIG. 9 is a front view thereof, shown in reduced scale in a folded and unused state.

The broken lines depict portions of the foldable face mask that form no part of the claimed design.

1 Claim, 9 Drawing Sheets
